UNITED STATES PATENT OFFICE.

LILBURN S. CLAITOR AND ROSS C. MAHAGAN, OF PETERSBURG, TEXAS.

TRACTION-ENGINE.

1,084,069.

Specification of Letters Patent.

Patented Jan. 13, 1914.

Application filed October 25, 1909. Serial No. 524,453.

To all whom it may concern:

Be it known that we, LILBURN S. CLAITOR and Ross C. MAHAGAN, citizens of the United States, residing at Petersburg, in the 5 county of Hale, State of Texas, have invented a new and useful Traction-Engine, of which the following is a specification.

The present invention appertains to a novel and improved traction engine or 10 tractor.

It is the object of the present invention to provide a novel or unique assemblage of the tractor frame or body, the steam engines for propelling the machine, the steam boiler, and 15 the traction wheels, whereby the combination of the said devices will be a highly desirable and efficient one, the frame or body being of such peculiar construction, as to enable the combination to be carried out to 20 the ends desired.

The invention has been illustrated in its preferred embodiment in the accompanying drawings, wherein:—

Figure 1 is a side elevation of the improved tractor. Fig. 2 is a longitudinal sectional view thereof. Fig. 3 is a transverse sectional view taken on the line 3—3 of Fig. 1. Fig. 4 is a transverse sectional view taken on the line 4—4 of Fig. 1.

In carrying out the invention there is provided a unique frame or body, embodying front and rear sections. The front and rear frame sections embody the respective side beams 1 and 5, the forward portions of the 30 rear beams 5 resting on the rear portions of the front beams 1, for a considerable extent. The forward ends of the beams 1 are mounted upon the steering axle 2 having the wheels 3 journaled on its ends, any suitable 35 means being provided for steering the axle 2, but inasmuch as the said steering means forms no part of the present invention, it need not be shown nor described. A tender 4 is mounted upon the forward portion 40 of the front frame section or its beams 1. Suitable bolts, or other securing members 6 are employed for clamping or securing the overlapping ends of the beams 1 and 5 together, whereby the overlapping portions 45 of the beams are firmly attached, and present relatively large bearing surfaces or bases for supporting the steam engines, as 50 hereinafter described.

Bearings 7 are secured to the bottoms of 55 the rear beams 5 in rear of the beams 1, and a rear axle or driving shaft 8 is jour-

naled through the bearings 7. Steam engines are carried at the outer sides of the overlapped end portions of the respective beams, the steam engines embodying the 60 cylinders 9, which are preferably attached to the end portions of the rear beams 5, although it is to be noted that the overlapped end portions of the front and rear beams provide relatively large bases for 65 holding the cylinders of the steam engines in position. The terminals of the shaft or axle 8 project beyond the beams 5 and have disks 10 fixed thereon. The disks are provided with the wrist pins 11, and the cross 70 heads 12 of the steam engines are operatively connected with the wrist pins 11 by the connecting rods or pitmen 13. The wrist pins 11 at the opposite sides are preferably set at such angles, as to prevent the 75 two engines from coming to dead center simultaneously, which would be objectionable.

Standards or pedestals 14 are mounted upon the side beams 5 of the rear frame section, preferably midway between the ends of the beam 5, and are provided at their upper ends with the trunnion bearings 15. The steam boiler 16 is disposed above the rear frame section between the pedestals 14, 80 and is provided at its sides with the trunnions 17 journaled in the bearings 15, whereby the boiler is pivotally supported over the rear frame section.

The steam boiler 16 is preferably of the 90 marine type, known as return fire tube boiler, wherein the stack 18 is located above the fire box 19. In this connection, it is to be observed that the fire box 19 depends between the overlapped portions of the beams 95 1 and 5, and faces the tender 4 or the front frame section. This is advantageous for the reason that the fire box is somewhat housed between the overlapped portions of the beams, and the engineer may be conveniently positioned on the front frame section, to feed the fuel into the fire box, it being noted that the front frame section is disposed on a lower level than the rear frame section.

The boiler 16 is provided with the usual steam dome 20, to which a pair of flexible pipes 21 are connected, the pipes 21 being connected to the inlet pipes 22 of the respective steam engines, by slip joint connections as indicated at 23. Thus, flexible connections are provided between the pivoted 105

boiler and the steam engines, in order that the boiler may be adjusted or swung without interfering with the operation of the engines.

5 An adjusting shaft 24 is journaled in bearings 25 secured on the forward ends of the beam 5, and stands in advance of the fire box 19. Arms 25 are secured to the terminals of the shaft 24, and are provided 10 with slots 27 at their free ends receiving studs 28 attached to the sides of the fire box 19. A gear segment 29 is attached to the shaft 24 adjacent one end and meshes with a worm 30 mounted upon vertically disposed 15 shaft 31 journaled to the forward end portion of one of the beams 5, and provided at its upper end with a hand wheel 32 accessible from the front frame section. It is to be observed in this connection, that the relation 20 of the beams of the front and rear frame sections, and the fire box of the pivoted boiler supported between the overlapped portions of the beams, is of peculiar advantage, for the reason that the adjusting means 25 connecting the sides of the fire box and the forward ends of the rear beams, has a unique relation therewith.

By the arrangement just described, it will be apparent that by rotating the shaft 31 30 through the medium of the hand wheel, the shaft 24 may be rotated so as to swing the arms 26 and to consequently swing the boiler. In this manner, the boiler may be constantly brought to a level position, when 35 the machine is traversing inclined or declined roads or surfaces.

40 A pair of traction wheels 33 are journaled between the rear beams 5 underneath the boiler and in rear of its fire box, the traction wheels 33 being journaled on the axle or shaft 8. The rims 34 of the traction wheels are relatively wide, and juxtaposed, so as to fill in the space between the beams 5. The rims 34 are also provided with ribs 35 45 for facilitating the tractive effort.

45 A compensating gear mechanism or differential 36 is located upon the axle 8 intermediate the ends thereof, and is also connected with the hubs of the traction wheels 33. This mechanism or differential comprises a master disk 36, which is fixed to the intermediate portion of the axle 8, and is provided at equal distances from its center, with a series of bevel pinions 38 journaled 50 for rotation in openings 37 and having their axes in a plane at right angles to the axis of the axle 8. Bevel gear wheels 39 are fixed to the inner ends of the hubs 40 of the traction wheels 33 and mesh with the bevel

pinions 38 carried by the master disk 36. 60 By this arrangement, when the axle or shaft is rotated by the steam engines, the traction wheels will be driven through the medium of the differential or compensating mechanism in order to permit the respective traction wheels to rotate at different velocities, as when the machine is rounding a curve, both of the traction wheels being driven under various conditions.

65 In some instances, it may be desirable that the traction wheels 33 be constrained to rotate in unison, and to this end, the master disk 36 is provided upon its periphery with perforated lugs 41 which are adapted to register with perforated lugs 42 carried by 75 the bevel gears 39 in order that securing bolts 43 may be passed through the lugs with the axle or shaft 8.

70 The salient or cardinal feature of the present invention resides in the provision of the peculiar frame, and the unique combination therewith of the steam engines, pivoted boiler, adjusting means for the boiler, traction wheels, and the connections between the boiler and steam engines. 85

Having described the invention, what is claimed is:—

80 In a tractor, a frame embodying front and rear sections, each frame section embodying side beams, the forward end portions of the rear beams resting on the rear end portions of the respective front beams, means for clamping the overlapped end portions of the beams together, steam engines carried at the outer sides of the overlapped end portions of the beams, pedestals carried by the rear beams, a steam boiler trunnioned between the pedestals over the rear frame sections and having its fire box depending between the overlapped end portions of the 90 beams and facing the front frame section, adjusting means operably connecting the front ends of the rear beams and the fire box of the boiler, traction wheels journaled between the rear beams under the boiler and in rear 95 of its fire box and operatively connected with the respective steam engines, and flexible connections between the boiler and steam engines. 100

105 In testimony that we claim the foregoing as our own, we have hereto affixed our signatures in the presence of two witnesses.
